UNITED STATES PATENT OFFICE.

EDGAR C. WHITE, OF BELMAR, NEW JERSEY.

SCREEN.

1,147,583.

Specification of Letters Patent. Patented July 20, 1915.

Application filed July 9, 1913. Serial No. 772,128.

To all whom it may concern:

Be it known that I, EDGAR C. WHITE, a citizen of the United States, residing at Belmar, in the county of Monmouth and State of New Jersey, have invented new and useful Improvements in Screens, of which the following is a specification.

The invention relates to screens and has for an object to provide a screen, preferably adapted for windows, to prevent the entrance of insects such as mosquitos into houses.

The invention embodies, among other features, a frame adapted for rigid engagement with the usual window casing in a manner which will not prevent the usual operation of the sashes, with a screen sash carried by the frame and operable in the same manner as a window sash, with means for normally locking an opening in the frame, and which is provided for the purpose of permitting the locking or unlocking of the window sashes without necessitating the moving of the screen sash, into an open position.

In the further disclosure of the invention reference is to be had to the accompanying drawings, constituting a part of this specification, in which similar characters of reference denote corresponding parts in all the views, and in which:

Figure 1 is a front elevation of a window casing, showing my device applied thereto, with the screen sash in closed position; Fig. 2 is a rear elevation, the screen sash being shown in partially open position; Fig. 3 is a horizontal sectional view taken on the line 3-3 in Fig. 1; Fig. 4 is a horizontal sectional view taken on the line 4-4 in Fig. 2; Fig. 5 is a vertical sectional view taken on the line 5-5 in Fig. 1, showing the manner of securing the frame to the window casing; and Fig. 6 is a horizontal sectional view taken on the line 6-6 in Fig. 1 and disclosing the closure for an opening in the frame.

Referring more particularly to the views, I disclose the usual window screen 10 having upper and lower window sashes 11 and 12 respectively mounted to slide thereon in the usual manner, the said sashes being dormally secured in locked position by a suitable catch 13 preferably carried by the lower

sash 12 to engage a socket 14 on the upper sash 11 and relatively lock the window sashes in closed position.

A frame 15 is supported on the window casing 10 and abuts against uprights 16 carried by the window casing and lying adjacent to the usual guide pieces 17 for the lower sash 12, the said frame 15 being secured in locked position on the casing by L-shaped securing members 18 passing transversely through the frame, with the lateral extensions of the members engaging the uprights 16, suitable thumb nuts 19 being threaded on the free ends of the members and, when screwed up, adapted to lock the frame 15 rigidly to the window casing.

The frame 15 has vertical slides 20, on which is mounted to slide a vertical screen sash 21, the said screen sash, however, when in closed position on the frame, being adapted to extend fully half the height of the same, a screen 22 being rigidly secured to the frame 15 to close the upper portion thereof, with the lower end of the screen 22 projecting downwardly to slightly overlap the screen sash 21 and which carries a screen 23, a plurality of cross bars 24 being rigidly secured to the frame 15 and to which the lower ends of the screen 22 are connected. A suitable knob 25 is secured to the screen sash 21 for the purpose of permitting of readily raising and lowering the sash and bolts 26 are carried by the sash to engage keepers 27 for securing the sash in lowered and locked position.

Referring to the views, it will be seen that the spaces between the cross bars 24 are covered by the screen 22 and at substantially the medial portions of the cross bars and between the same a portion of the screen 22 is cut away to provide an opening 28 in the horizontal plane of the catch 13 when the window sashes 11 and 12 are in relatively closed position so that the operator on the inner side of the casing can insert the hand through the opening 28 for the purpose of manipulating the catch 13 in order to lock or unlock the sashes 11 and 12. Now in order to prevent the egress of insects such as mosquitos or the like through the opening 28 a closure is mounted to swing on one of the cross bars 24, the said closure when in horizontal position being adapted to engage

members 30 secured to the cross bars 24 and which not only guide the closure from an open to a closed position but retain the same in closed position so that the closure will close the opening 28, as shown.

Now from the foregoing description it will be apparent that when the screen sash 21 is in lowered and closed position, the window sashes 11 and 12 can be locked or unlocked by manipulating the catch 13, this being accomplished by first moving the closure 29 into open position and then inserting the hand through the opening 28, to grip the catch, it being thus apparent that the window sashes 11 and 12 can be locked or unlocked without necessitating the raising or lowering of the screen sash. Furthermore, when the screen sash is in lowered position the upper edge thereof will lie in the horizontal plane of the lower cross bar and will fit snugly against the same to prevent any insects from passing through the almost unnoticeable space between the cross bar and the upper edge of the screen sash.

The frame 15 can be readily applied to the ordinary form of window casing and can be as readily removed therefrom without marring the casing or necessitating any extensive carpentry work and also without in any manner disturbing the proper operation of the window sashes of the casing, it being understood that the downward movement of the screen sash is limited by

the usual sill 31 of the window casing 10 and against which the screen sash abuts. 35

Having thus described my invention, I claim:

1. In a device of the class described, a frame, means for removably securing said frame to a window casing, said means including a series of L-shaped members projecting transversely through the frame and having lateral projections to engage the casing, nuts threaded on said members for tightening the lateral projection thereof to said casing. 40

2. In a device of the class described, a rectangular frame detachably secured within a window casing, a pair of transverse parallel cross bars rigidly secured to and at 50 the medial portion of said frame, upper and lower screens, the lower screen being slidably mounted within said frame and the upper screen being rigidly secured within said frame, and the mesh of the latter mentioned screen having its lower transverse edge fixedly secured to one of said cross bars, and means carried by said bars for permitting an entrance therethrough and through 55 the upper screen section. 60

In testimony whereof I affix my signature in presence of two witnesses.

EDGAR C. WHITE.
